Primary Examiner — John Windmuller(74) *Attorney, Agent, or Firm* — Walter M. Egbert, III; Gerard M. Donovan; Reed Smith LLP(57) **CLAIM**

We claim the ornamental design for a GPS device, as shown and described.

DESCRIPTION

FIG. 1 is a perspective view of a GPS device showing our new design;

FIG. 2 is a right side view thereof;

FIG. 3 is a left side view thereof;

FIG. 4 is a top view thereof;

FIG. 5 is a bottom view thereof;

FIG. 6 is a front view thereof;

FIG. 7 is a rear view thereof; and,

FIG. 8 is a perspective view thereof.

The subject matter shown in broken lines forms no part of the claimed design.
